METHOD OF AND APPARATUS FOR MAKING
COLD CATHODE FLUORESCENT LAMPS OR
THE LIKE

Carl Herzog, Belleville, N. J.

Application March 7, 1944, Serial No. 525,446

11 Claims. (Cl. 316—11)

My invention relates to a method of and apparatus for producing electronic devices, such as gaseous discharge tubes including cold cathode fluorescent lamps, neon lamps, radio tubes or the like, and to such devices.

An important object of the invention is to provide a continuous method for performing the various steps in producing the finished product, such as a cold cathode fluorescent lamp, and will reduce the manipulation of the tube to the minimum.

A further object of the invention is to provide a method of the above mentioned character which will eliminate the baking of the coating of the tube in a furnace as a separate method.

A further object of the invention is to provide a method which will evacuate the tube and seal in the electrode at the same time.

A further object of the invention is to provide a method which will materially reduce the cost of baking cold cathode fluorescent lamps.

A further object of the invention is to provide apparatus for use in the practice of the method.

A further object of the invention is to so mount the tubular electrode shell upon the contact extension of the retainer or retainer for reducing heat transfer from the electrode shell.

Other objects and advantages of the invention will be apparent during the course of the following description.

In the accompanying drawings, forming a part of this application and in which like numerals are employed to designate like parts throughout the same.

Figure 1 is a central vertical longitudinal section through apparatus embodying my invention, showing the baking steps.

Figure 2 is a similar view through the tube, partly diagrammatic, showing the vacuum baking.

Figure 3 is a similar view showing sealing the bottom end of the tube.

Figure 4 is a similar view showing cutting off the bottom end of the tube.

Figure 5 is a similar view showing gas insertion into the tube.

Figure 6 is a similar view showing mercury insertion into the tube.

Figure 7 is a similar view showing sealing the top end of the tube.

Figure 8 is a similar view showing cutting off the top end of the tube and producing the finished product.

Figure 9 is an enlarged central longitudinal section through the completed lamp.

Figure 10 is a perspective view, parts broken away, showing a modified manner of mounting the cathode upon the contact extension of the retainer.

5 Figure 11 is a similar view showing a further modified manner of mounting the cathode upon the retainer.

Figure 12 is a similar view showing a further modified manner of mounting the cathode upon the retainer, and

10 Figure 13 is a central vertical section, upon an enlarged scale, through the tube at the point of fusing the tube to the retainer, parts broken away.

15 In the drawings, wherein for the purpose of illustration is shown a preferred embodiment of my invention, the numeral 10 designates a glass tube, constituting the envelope of the cold cathode fluorescent lamp. This tube may be of any suitable diameter and length. These tubes are frequently a half inch in diameter and eight feet long, although the dimensions may be varied.

20 The inner surface of the tube 10 is covered or coated with a coating composition containing a finely divided luminescent or fluorescent material, and this coating is dried. I may employ the coating composition disclosed in the patent to T. M. Cortese, 2,318,060, and this coating may be applied and dried in accordance with the

25 method disclosed in the Cortese patent. However, the coating is not baked in a separate oven, but the baking occurs as a step in my method. The tube 10, Figure 1, has the coating composition 11, which may be the fluorescent coating composition disclosed in the Cortese patent, extending originally throughout its entire length, and dried but not baked, and this dried coating is removed from the ends of the tube 10 to points 12, leaving clean or uncoated zones 13 and 14.

30 The tube 10 with the dried interior coating 11 is vertically arranged with its opposite ends open and held within a holder 15 to be supported thereby.

35 Disposed within the opposite ends of the tube 10 are electrodes, including electrode shells 16. Each electrode shell is made of the purest iron obtainable and the interior of the shell is coated with an electron emitting material, as is well known. Each electrode shell is press fitted into a top cup-shaped contact extension 17 of a retainer 18, surrounding the electrode shell and spaced therefrom. The retainer 18 has a larger diameter than the electrode shell 16 and has a smaller diameter than the tube 10, and the tube is fused 40 to the retainer, to provide a vacuum-tight joint,

as will be explained. The retainer forms a ring or band extending radially beyond the electrode shell 16. If desired, the electrode shell 16 may be welded to the contact extension 17. The retainer 18 is made of a special commercial chrome-iron alloy which has the same expansion coefficient as glass. The retainer 18 and the contact extension 17 have their ends imperforate, as shown.

I also contemplate using the form of electrode which is an integral unit, as shown in Figure 21 of my copending application for Method of and apparatus for producing cold cathode fluorescent lamps and to such lamps, filed January 26, 1944, Serial No. 519,666.

I may employ the electrode shown in Figure 10. In this figure, 16' is an electrode shell, identical with the shell 16 and having a closed end 17', which is welded to a wire 18'. This wire is welded to the end of the contact extension 17 of the retainer 18. The wire 18' supports the electrode shell 16' in spaced concentric relation to the contact extension 17 and the retainer 18.

In Figure 11, I have shown a slightly different arrangement wherein wires 19' are welded to the sides of the electrode shell 16' and to the bottom of the retainer 18. The arrangement is otherwise identical.

In Figure 12, I have shown a further similar arrangement, wherein a radial ribbon or strap 20' is welded to the end 17' of the electrode shell and extends outwardly beyond the same and is welded to the bottom of the retainer 18. The arrangement is otherwise identical with that shown in Figure 10.

The advantage of the electrode shown in Figures 10, 11 and 12, is that the electrode shell is spaced from the contact extension 17 and retainer 18 and connected therewith by the wire or wires or ribbon and the amount of heat which is transmitted by conduction from the shell 16' to the contact extension or retainer 18 is reduced. This is advantageous after the lamp has been made and is operating in use.

The electrode shell 16' corresponds to the electrode shell 16 and the same retainer and contact extension is used.

I will now describe the operating units of apparatus which is used in the practice of the method. The operating units are designated generally by the numerals 19 and 20. Each operating unit includes an outer block 21, having a reduced inner end 22, which is screw-threaded, and provided with a main vertical chamber 23. This main vertical chamber receives compressible packing 24, which may be rubber, asbestos, or a mixture of the same, or any other suitable material for effecting a vacuum-tight joint with the glass tube 10. A follower ring 25 is movable into the chamber 23 to compress the packing 24. The chamber 23 leads into a chamber 26. Each block is provided with a vertical opening 27 to receive the shank 28 of a clamp or socket 29. This socket 29 may be resilient. The shank 28 is electrically insulated upon the block 21 by an insulating sleeve 30. The shanks 28 are connected with the opposite poles of a source of current by lead wires 32, for a purpose to be described. Each reduced screw-threaded extension 22 has a cap 33 mounted thereon and having screw-threaded engagement therewith, to shift the follower ring 25 and compress the packing. This cap is provided with a water space or jacket 34, and the coolant may enter at the pipe 35 and leave by the pipe 36.

The unit 20 is provided with a hot air port

37, leading into the chamber 26 and this hot air port is connected with a pipe 38, having a cut-off valve 39 connected therein. The pipe 38 leads to a source of hot air and the hot air is supplied through the pipe 38 so that it may enter the glass tube 10 at substantially 400° C. The unit 20 also has a vacuum port 40, in communication with the chamber 26 and connected with a pipe 41, having a cut-off valve 42 connected therein. The pipe 41 is connected with a source of vacuum.

The unit 19 has a tube 43, connected therewith, and this tube communicates with a port 44, leading into the chamber 26. The tube 43 has a hot air discharge tube 45 and a gas inlet tube 46, connected therewith. A rotary valve 47 is arranged at the union of the tubes 43, 45 and 46, and may be manipulated to place tube 43 in communication with tube 45, or tube 43 in communication with tube 46, or to cover the bore of the tube 43 or tube 46.

The unit 19 is provided in its upper end with a well 48 for holding mercury and has a tapered recess 49 beneath the well to receive a tapered rotary valve element 50. This valve element is turned by a stem 51 having a crank 52 and is urged upon its seat by a spring 53. The valve element 50 has diametrically oppositely arranged pockets 54, for receiving measured amounts of the mercury and discharging the same into an inclined port 55, leading into the chamber 26. The well 48 is in communication with a vertical port 56 having a horizontal branch 57 which leads into the recess 49 and feeds the mercury into the pocket 54. The vertical port 56 discharges at its lower end into a horizontal recess 57', arranged beneath the valve element 50. It is thus seen that the mercury contacts with the upper and lower ends of the valve element 50 and seals these ends, whereby a vacuum-tight joint is effected.

The practice of the method is as follows:

I take the glass tube 10 having the dried unbaked fluorescent coating 11 and its ends open, and insert the same in the holder 15, Figure 1, which vertically supports the tube. The electrode shells 16 are held by the sockets or clamps 29 by inserting the contact extensions 17 into these sockets. The socket or clamp 29 has a smaller diameter than the retainer 18, as clearly shown in Figure 13. The units 19 and 20 are now brought into proximity to the opposite ends of the tubes 10 and the electrode shells 16 are inserted into such opposite ends. The sockets 29 retain the electrode shells in spaced concentric relation to the tube 10. The ends of the tube 10 are passed into the packing 24 within the chambers 23. The units 19 and 20 may be supported by any suitable means. The caps 33 are now screwed up so that the follower rings 25 place the packing under compression and form vacuum-tight joints with the tube 10. The coolant is properly circulated through the caps 33. The valve element 50 may now be in the position shown in Figure 1, whereby the inner pocket 54 is empty while the outer pocket 54 is filled with the mercury. The valve element 47 may now be in the position shown in Figure 1, whereby the port 44 is in communication with the hot air discharge port 45, while the port 46 is covered. The valve element 42 now covers port 40, while valve element 39 is open. Hot air is now supplied through the pipe 38 and circulates through the glass tube 10 and discharges from the glass tube through the pipe 45. This hot air thus supplied to the glass tube has a temperature of substantially 400° C. This hot air bakes the dried fluorescent coating 11 in whole or in part. The

baking treatment may continue for about half an hour. During this baking operation, any gases or the like liberated from the coating 11 pass out with the hot air through the pipe 45. It is advantageous to bake the coating in this manner, as the tubes are long and require a large furnace for baking. The baking in accordance with my method does not plasticize the tube.

After the baking operation, Figure 2, the valve 39 is closed and valve 47 turned to cover port 44, 10 and valve 42 turned to the open position. The interior of the glass tube 10 is now placed in communication with a source of vacuum and is suitably evacuated. During this evacuation, the electrode shells 16 are connected with the opposite poles of the source of current, through the wires 32. This is done to heat the electrode shells 16 and drive off undesirable gases and impurities. When the electrode shells 16 are thus connected with the opposite pole of the source of current, of a suitable character, they become highly heated and the tube 10 is heated, which aids in baking the coating 11. This heating action of the electrode shells 16 is continued for a suitable length of time, indicated by a small piece of paper contacting with the heated tube 10 becoming browned or partly charred. When this occurs, the electrode shells 16 are disconnected from the source of current.

After this and when the proper vacuum is attained within the tube 10, Figure 3, the valve 42 is turned to cover the port 40 and hold the vacuum within the tube. Before the tube has materially cooled, a high frequency coil A is brought into a position for surrounding the lower end of the tube and the lower electrode shell 16, and when the current is turned on, the coil will heat the electrode shell 16 and retainer 18 by induction. This electrode shell and retainer may be heated to a high point and the heat radiating from the same will heat the adjacent portion 57^a of the tube, and this portion 57^a will be plasticized and drawn inwardly by the action of the vacuum within the tube 10. This portion 57^a will be then become fused to the retainer 18 for forming a vacuum-tight joint therewith. This action may be aided by the use of forming jaws, if necessary.

The lower end 58 of the tube, Figure 4, is now severed from the tube by knives 59. These knives will not engage the clamp 29 which has a smaller diameter than the retainer 18, as shown in Figure 13.

The valve 47 is now turned to place the tube 46 in communication with the port 44, to supply a small amount of inert gas, such as argon or neon, into the tube 10, Figure 5. The amount of inert gas thus supplied is small and does not perceptibly change the degree of vacuum in the tube. The valve 47 is now turned to the neutral position to cover the port 44.

By this time, the temperature of the tube 10 is materially reduced and may be at approximately room temperature, Figure 6. The valve element 50 is now turned to introduce the measured amount of mercury into the port 55 and this mercury drops to the bottom of the tube 10. This measured amount of mercury is ordinarily a ball of slightly less than $\frac{1}{2}$ " in diameter.

The high frequency coil A, Figure 7, is now applied to the top of the tube 10 adjacent to the upper electrode shell 16, and this electrode shell is highly heated by the action of the coil and the heat radiating from the shell 16 and retainer plasticizes the adjacent portion 60 of the tube, which is drawn inwardly by the vacuum within the tube and becomes fused to the retainer 18. This pro-

vides a vacuum tight joint and the action may be aided by forming jaws if necessary.

The upper end 61 of the tube, Figure 8, is now severed by the blades 62.

Figures 8 and 9 show the complete lamp. The electrode shells 16 are arranged within the opposite ends of the tube 10 and have their parts or retainers sealed therein to provide vacuum-tight joints. The retainers 18 hold the electrode shells in spaced concentric relation to the tube 10. The contact extensions 17 project outwardly beyond the ends of the tube 10, for engagement with the socket terminals, for supplying current to the lamp when in use.

When the electrodes embodying the cathode shells 16' and shown in Figures 10, 11 and 12, are used, the coil A heats principally the retainer 18, which, in turn, heats and plasticizes the tube 10. All other steps of the method remain identical with those shown and described.

It is to be understood that the apparatus here-with shown and described is to be taken as a preferred embodiment of the same, and that various changes in the shape, size, and arrangement of parts may be resorted to, and that changes may be resorted to in the order of the steps of the method, and in the shape, size and arrangement of parts of the cathode units, without departing from the spirit of my invention or the scope of the subjoined claims.

Having thus described my invention, I claim:

1. The method of making a cold cathode fluorescent lamp or the like, comprising supporting a glass tube having its opposite ends open and its inner surface coated with an unbaked fluorescent compound, introducing electrodes into the tube near its ends, circulating hot air through the tube to bake the coating, evacuating the tube, connecting the electrodes with a source of current to heat them and the tube to aid in the baking, heating the electrode near one end of the tube by induction and causing the same to heat and plasticize the adjacent portion of the tube and fusing such adjacent portion to the electrode, cutting off the outer adjacent end of the tube, introducing an inert gas into the tube, introducing mercury into the tube, heating the other electrode by induction and causing the same to heat and plasticize the adjacent portion of the tube and fusing such adjacent portion to the electrode, and cutting off the outer adjacent portion of the tube.

2. The method of making a cold cathode fluorescent lamp or the like, comprising supporting a glass tube having its opposite ends open and its inner surface coated with an unbaked fluorescent compound, introducing electrodes into the tube near its ends and holding them generally concentric with relation to the tube, circulating hot air through the tube to bake the coating, evacuating the tube, connecting the electrodes with a source of current to heat them and the tube to aid in the baking, heating the tube adjacent to one electrode to plasticize the same and fuse it to the electrode, cutting off the outer adjacent end of the tube, introducing an inert gas into the tube, introducing mercury into the tube, heating the tube adjacent to the other electrode to plasticize the same and fuse it to such electrode, and cutting off the outer portion of the tube.

3. The method of making a cold cathode fluorescent lamp or the like, comprising supporting a glass tube having its opposite ends open and its inner surface coated with an unbaked fluorescent compound, introducing electrodes into the tube near its ends, the electrodes having retainers ex-

tending radially beyond the same, supporting the electrodes within the tube, circulating hot air through the tube to bake the coating, evacuating the tube, connecting the electrodes with a source of current to heat them and the tube to aid in the baking, heating the tube adjacent to one electrode to plasticize the same and fuse it to the retainer of such electrode, cutting off the outer end of the tube adjacent to such retainer, introducing an inert gas into the tube, introducing mercury into the tube, heating the tube adjacent to the other electrode to plasticize it and fuse the same to the retainer of such electrode, and cutting off the outer portion of the tube adjacent to the retainer of the last named electrode.

4. The method of making a cold cathode fluorescent lamp or the like, comprising supporting a glass tube having its opposite ends open and its inner surface coated with a fluorescent compound, introducing electrodes into the ends of the tube and supporting them near and spaced from such ends, evacuating the tube, connecting the electrodes with a source of current during the evacuation, heating one electrode by induction and causing the same to heat and plasticize the adjacent portion of the tube and fusing such adjacent portion to the electrode, cutting off the outer adjacent end of the tube, introducing an inert gas into the tube, introducing mercury into the tube, heating the other electrode by induction and causing same to heat and plasticize the adjacent portion of the tube and fusing such adjacent portion to the electrode, and cutting off the outer adjacent portion of the tube.

5. In the method of making a cold cathode fluorescent lamp or the like, the steps of supporting a glass tube having its inner surface coated with a fluorescent compound and having its ends open, introducing into the open ends of the tube electrodes having radially enlarged bands, and connecting one open end of the tube with a source of vacuum to evacuate the tube, heating the electrodes by electrical induction and causing them to heat and plasticize adjacent portions of the tube and fusing such adjacent portions to the bands for providing vacuum-tight joints.

6. In the method of making a cold cathode fluorescent lamp or the like, the steps of supporting a glass tube having its opposite ends open and its inner surface coated with a fluorescent compound, circulating hot air through the tube to bake the compound, supporting electrodes within the tube near its ends, and heating the electrodes by electrical induction and causing them to heat and plasticize the adjacent portions of the tube for fusing the adjacent portions to the cathodes.

7. In the method of making a cold cathode fluorescent lamp or the like, the steps of supporting a glass tube having its ends open, supporting electrodes within the tube near its open ends, evacuating the tube while its ends are open, and heating each electrode by electrical induction and causing the same to heat and plasticize the adjacent portion of the tube which is drawn inwardly by the vacuum and fused to the electrode.

8. The method of making a fluorescent lamp or the like, comprising supporting a glass tube having its opposite ends open and its inner surface coated with an unbaked fluorescent compound in an upstanding position, supporting electrodes and

5 retainers for the electrodes which extend radially beyond the electrodes in the tube near its open ends and spacing the retainers from the tube for providing passages, introducing hot air into one end of the tube and circulating the same through the passages and tube and discharging the same from the opposite end of the tube to bake the fluorescent coating, evacuating the tube while its opposite ends are open, heating the tube adjacent to one retainer to plasticize the tube and fuse the tube to the retainer for producing a vacuum-tight joint, introducing an inert gas into the open end of the tube, introducing mercury into the open end of the tube, heating the tube adjacent to the other retainer to plasticize the tube and fusing the tube to the retainer for forming a vacuum-tight joint, the retainers holding the electrodes spaced from the tube.

9. The method of making a cold cathode fluorescent lamp or the like, comprising introducing into body portions having chambers the open ends of a glass tube having its inner surface coated with an unbaked fluorescent compound, supporting within the tube near its ends electrodes, introducing hot air into one chamber and circulating the same through the tube and discharging the hot air from the tube into the other chamber, evacuating the tube through one chamber, connecting the electrodes with a source of current, heating one electrode by electrical induction and causing the same to heat and plasticize the adjacent portion of the tube and fusing such adjacent portion to the electrode, introducing an inert gas into the tube through one chamber, introducing mercury into the tube through one chamber, and heating the other electrode by electrical induction and causing the same to heat and plasticize the adjacent portion of the tube and fusing such adjacent portion to the electrode.

10. In the method of making a cold cathode fluorescent lamp or the like, the steps of supporting a glass tube having one end open and its inner surface coated with a fluorescent compound, introducing into the open end of the glass tube a tubular electrode having a metal band extending radially beyond the tubular electrode, evacuating the tube through the open end of the tube, heating the metal band by electrical induction and causing the metal band to heat and plasticize the adjacent portion of the glass tube and fusing such adjacent portion of the glass tube to the metal band for providing a vacuum-tight joint, the metal band holding a tubular electrode spaced from the glass tube.

11. In the method of making a fluorescent lamp or the like, the steps of supporting a glass tube having one end open and its inner surface coated with a fluorescent compound, introducing into the open end of the glass tube an electrode having a metal band extending radially beyond the electrode, evacuating the tube through the open end of the tube, heating the metal band by electrical induction and causing the metal band to heat and plasticize the adjacent portion of the glass tube and fusing such adjacent portion of the glass tube to the metal band for providing a vacuum-tight joint, the metal band holding the electrode spaced from the glass tube.
